UNITED STATES PATENT OFFICE.

ANATOLE DES CRESSONNIÈRES AND ERNEST DES CRESSONNIÈRES, OF
BRUSSELS, BELGIUM.

MACHINE FOR KNEADING SOAP.

SPECIFICATION forming part of Letters Patent No. 617,282, dated January 3, 1899.

Application filed August 16, 1898. Serial No. 689,069. (No model.)

To all whom it may concern:

Be it known that we, ANATOLE DES CRESSONNIÈRES and ERNEST DES CRESSONNIÈRES, subjects of the King of Belgium, residing at 5 Brussels, in the Kingdom of Belgium, have invented a new and useful device for automatically feeding machines for kneading or compressing soap and the like plastic substances, (for which patents have been filed in 10 Belgium December 23, 1897, accepted No. 132,688; in Germany February 26, 1898; in England February 26, 1898; in France February 25, 1898; in Sweden March 2, 1898; in Hungary March 10, 1898, and in Austria March 15, 15 1898,) of which the following is a full, clear, and exact description.

The device for automatically feeding machines for kneading or compressing soap and the like plastic substances which forms the 20 object of the present application is a notable simplification of the arrangement described in another application for Letters Patent filed July 7, 1896, Serial No. 598,326, which allows the crusher therein described to be dispensed 25 with and replaced by a single feed-roller, which modification has the further advantage of being applicable to all existing machines of this kind, as well as to new machines.

In the previous patent referred to it was 30 explained that the machine was fed by the crusher with a view to causing the material to fall in a disintegrated condition between the spirals of the helix for the purpose of preventing it caking and doing away with the hand-labor for feeding it therein. For this 35 object a corrugated knife or scraper removed the material in shavings from the last cylinder of the crusher and it fell between the spirals of the helix, which carried it below 40 the knife and toward the matrix. Nevertheless it was unavoidable by reason of the shape and arrangement of the said knife that the quantity of material discharged from the last cylinder corresponded exactly to the 45 quantity carried away by the matrix, as without this condition the free space between the knife and the perimeter of the helix would become filled with soap more or less caked and compressed, which would finally form a 50 spiral or helix of soap which would constantly

fill the helix and prevent it conveying the fresh material fed in, so that the yield was limited to the maximum quantity of movable soap that the helix could convey.

According to the present invention, however, this maximum yield is considerably increased by an improved arrangement of feed whereby the quantity of soap conveyed is compacted or compressed into the helix under the action of a knife, as may be seen by 60 reference to the accompanying drawings, in which—

Figure 1 is an end view, partially in section, and Fig. 2 a longitudinal section, of the kneader or compressor with automatic feed. 65

The vacant space between the knife R, the perimeter of the helix S, and the part of the cylinder T containing the helix is entirely avoided by reason of the circular form of the knife, which instead of being fixed on a lateral extension of the wall of the cylinder is fixed on a flange B, running from the edge of the cut-away wall of the cylinder T along the whole length of the knife, which latter thus continues the wall of the cylinder in conformity with the perimeter of the helix up to a point below the tangential line of the single feed-roller C, which has the same diameter 70 as the helix S and the perimeter of which is tangential with the helix by reason of its 75 trunnions being mounted in brackets K, projecting from the cylinder T, which is open above and surmounted by a hopper E. Further, the helix S and the roller C have the same speed of rotation, which is transmitted 80 to them by suitable driving-gear H in such a way as to cause them to revolve in opposite directions.

The working will be easily understood from the foregoing. 90

The material to be kneaded or condensed into a roll or extruded column is conveyed promiscuously into the hopper E and falls directly onto the helix S, which tends to carry it toward the roller C, which latter, revolving in an opposite direction, compresses it and piles it between the spirals of the helix, the interstices of which thus convey the maximum of material which passes in front of the internal smooth face of the curved 95 100

knife R, the full cutting edge of which latter scrapes off the soap adhering to the roller in such a way that said roller always acts in a clean or bare condition on the fresh material
5 which is introduced into the hopper and constantly drawn between the spirals of the helix by the coöperation of the helix with the feed-roller, which thus plays the part of the human hand formerly necessary in this dangerous
10 operation. This simple arrangement for automatically feeding machines for kneading or compressing soap and the like into a roll or extruded column is only possible for such a sticky substance as soap on condition that
15 the cylinder has no extravasations for the reasons hereinbefore explained, and therefore the cut-away wall of the cylinder oppo-

site the roller must be itself sharpened as a scraper in the form of a knife R, having the same shape as the cover.

20

We declare that what we claim is—

A soap-machine comprising a helix, a helix-containing cylinder having a cut-away wall, a feed-roller and a knife having a cutting edge of the same form as the cylindrical wall 25 of the helix-containing cylinder; substantially as described.

In witness whereof we have hereunto set our hands in presence of two witnesses.
